JAMES TRACY, OF BREWER'S VILLAGE, MAINE.

Letters Patent No. 63,340, dated March 26, 1867.

IMPROVEMENT IN SAW-MILLS.

The Schedule referred to in these Letters Patent and making part of the same.

TO ALL WHOM IT MAY CONCERN:

Be it known that I, JAMES TRACY, of Brewer's Village, in the county of Penobscot, and State of Maine, have invented a new and improved Machine for Hoisting and Canting Lumber in a Saw-Mill; and I do hereby declare that the following is a full, clear, and exact description thereof, which will enable others skilled in the art to make and use the same, reference being had to the accompanying drawings, forming part of this specification, in which—

Figure 1 is a cross-section of an edging-saw frame showing the arrangement of my improved hoisting machinery.

Figure 2 is a side view of the same.

Similar letters of reference indicate like parts.

This invention relates to improvements in machinery to be connected with a gang-saw mill, for canting and hoisting the timber after it has been cut into plank upon the table of a circular saw for edging the plank. This operation is usually performed by hand, by several men, with great labor, whereas by the application of my improved machinery the manual labor is saved and the operation is performed with great dispatch.

A represent the frame of a circular-saw mill for edging plank connected with a gang-saw mill; C is the circular saw, and D the table; E is the stock or lumber, after having been sawed in the gang-saw mill, which is to be edged by the circular saw. The lumber has to be lifted upon the table D for the purpose of edging or squaring the edges of the plank, and this operation is readily accomplished by the hoisting apparatus as follows: F is a driving-pulley which is connected with the machinery of the saw-mill to give it motion, and is placed at any convenient point, from which pulley passes a belt, a, to a small pulley, b, on the end of a shaft, c, hung in a frame, d. On the shaft c, within the frame d, is placed a friction-pulley, e, over which is hung a smaller friction-pulley, h, on a shaft, m, which carries at the opposite end a pinion, n, that engages in the spur-wheel n', on the shaft of which is the drum p, for winding the chain r that passes over the pulleys s s', above the edging-table, and falling centrally over the stock or lumber E, also passes through a single block and sheath i attached to the timber-hooks g. One end of the shaft m passes through a slot on the side of the frame d next the friction-pulley h, and is hung in the short arm of a lever, k, the long arm of which extends back under the floor G of the saw-mill, on which the lumber E is lying; and the end of the lever projects above the floor or is placed in some convenient position for the workman to place his foot upon it to depress it and operate the hoisting machinery. The shorter arm of the lever is turned downward and inward, and to it is secured the shaft m bearing the friction-pulley h. A spring, k', is secured to the frame near the pivot of the lever k, and bears against the inner side of its longer arm. Now when it is desired to raise the stock or lumber upon the edging-table D, the timber-hooks g are placed about centrally on the part to be edged, one man being stationed at each end of the lumber, when the man at the head nearest the circular saw puts his foot on the end of the lever k and presses it slightly, which throws the small friction-pulley h against the larger friction-pulley e, the motion of which is constant, and thus it receives rotation, carrying with it the pinion n on the same shaft m, turning the drum p by the spur-wheel n', and winding on it the chain r; which passes over the pulleys s s', thus hoisting the lumber over the table to be swung into place by the workmen; the head man's foot being removed from the lever k, the hoisting apparatus is thrown out of gear. By the same operation the lumber can be canted or the lower part of the stock turned over and laid with the widest side down upon the edging-table, by attaching the hoisting-clamp to chain-dogs properly adjusted.

Having described the construction of my invention, and its operation, I claim as new—

Applying the spring k' to bent-lever K, for the purpose of throwing the friction-pulleys out of contact, substantially as described.
